(57) **CLAIM**

The ornamental design for a bandage with insert, as shown and described.

DESCRIPTION

FIG. 1 is a top, front perspective view of a bandage with insert of the new design;

FIG. 2 is an exploded top front perspective view thereof;

FIG. 3 is a bottom rear perspective view thereof;

FIG. 4 is a front elevation view thereof;

FIG. 5 is a rear elevation view thereof;

FIG. 6 is a left elevation view thereof;

FIG. 7 is a right elevation view thereof;

FIG. 8 is a top plan view thereof;

FIG. 9 is a bottom plan view thereof;

FIG. 10 is a top, front perspective view of the insert from FIG. 1 of the new design;

FIG. 11 is a bottom rear perspective view thereof;

FIG. 12 is a front elevation view thereof;

FIG. 13 is a rear elevation view thereof;

FIG. 14 is a left elevation view thereof;

FIG. 15 is a right elevation view thereof;

FIG. 16 is a top plan view thereof; and,

FIG. 17 is a bottom plan view thereof.

The break lines in FIGS. 1-5 & 8-9 indicate that the appearance of any portion of the bandage with insert between the break lines forms no part of the claimed design.
